CLAIM

The ornamental design for a conveyor belt edge guard, as shown and described.

DESCRIPTION

FIG. 1 is a perspective view of a conveyor belt edge guard, showing my new design;

FIG. 2 is a front elevational view thereof;

FIG. 3 is a rear elevational view thereof;

FIG. 4 is a top plan view thereof;

FIG. 5 is an enlarged view of the circled portion in FIG. 4;

FIG. 6 is a bottom plan view thereof;

FIG. 7 is an enlarged view of the circled portion in FIG. 6;

FIG. 8 is a left side elevational view thereof;

FIG. 9 is an enlarged view of FIG. 8;

FIG. 10 is a right side view thereof; and,

FIG. 11 is an enlarged view of FIG. 10.

The dashed broken lines show portions of the conveyor belt edge guard that form no part of the claimed design. The conveyor belt edge guard is shown with symbolic breaks in its length. The appearance of any portion of the article between the break lines forms no part of the claimed design.
